UNITED STATES PATENT OFFICE.

FRANK ASPDEN, OF OCEAN FALLS, BRITISH COLUMBIA, CANADA.

FEED-MIXING MACHINE.

Application filed August 27, 1924. Serial No. 734,447.

To all whom it may concern:

Be it known that I, FRANK ASPDEN, a subject of the King of Great Britain, and a resident of Ocean Falls, in the Province of British Columbia, Canada, have invented certain new and useful Improvements in Feed-Mixing Machines, of which the following is a specification.

My invention relates to improvements in feed mixing machines, with more particular reference to machines for mixing poultry, cattle, or other feeds, although it may be used with equal facility for other analogous purposes, and the object of my invention is to devise a machine of this character which is simple, inexpensive, and highly efficient and the use of which enables such feeds to be mixed thoroughly and expeditiously and which is of the utmost convenience and utility.

I attain this object by the construction illustrated in the accompanying drawings in which—

Fig. 1 is an end view of the machine, in outside elevation.

Fig. 2 is an end view in sectional elevation, taken through the vertical centre line.

Fig. 3 is a front view in sectional elevation, taken through the line 3—3 of Fig. 2. Similar figures of reference indicate similar parts throughout the several views.

The machine consists of a mixing chamber 1 enclosed in a casing 2, the chamber having an upper inlet opening 3 and a lower discharge opening 4, which openings are normally closed by doors 5 and 6 respectively mounted at one side of their respective openings by spring hinges 7 and 8 of any well-known approved type adapted to maintain the doors normally closed. Through the chamber 1 and centrally of the same extends longitudinally a rotatable shaft 9, which shaft projects at its opposite ends exteriorly of the casing 2 and is provided on one end with a pulley 10 and at its opposite end with a gear 11, which gear meshes with gears 12 and 13 mounted above and below it and rotatably carried in bearings 14 and 15 secured to the side of the casing, as shown in Fig. 3.

Secured to the shaft 9 within the chamber 1 and suitably spaced apart thereon are two spiders 16 and 17 having as many radially extending arms 18 and 19 as may be desired; in the drawings each spider has, for the purpose of illustration, six arms

equidistantly spaced apart, and to these arms are secured, as shown in Fig. 3, six mixing plates, 20, 21, 22, 23, 24, and 25, which are preferably concaved on the side facing the direction of their rotation, as indicated in Fig. 2. These plates are formed broader at one end than at the other and they are arranged alternately, when the machine is assembled, as shown in Fig. 3, that is, the broad ends of plates 20, 22, and 24 are at the left hand side of the machine when in the position shown in Fig. 3, and the narrow ends of plates 21, 23, and 25 are at the right hand. The plates are also arranged to lie at their narrow ends closer to the shaft than at their broad ends so that their edges are therefore angularly inclined with relation to the shaft axis.

Mounted over the opening 3 is a hopper 75 which may, if preferred, be subdivided into a plurality of chambers by partitions 27 so that each chamber may be filled with an ingredient different from those in the other chambers; such subdivision, however, is optional.

Any suitable means for opening the respective inlet and discharge doors 5 and 6 may be employed, such as an arm 28 secured to the outer face of the gear 12 which contacts at predetermined intervals in the rotation of the gear with an arm 29 extending at its outer end, as at 30, through a slot 31 in the side of the machine and connected at its inner end to the underside of the inlet door, as at 32, thus moving the arm 29 along the slot and drawing the door 5 downwardly, the spring hinge 7 returning the door to the closed position when the arm 28 passes the end 30 of arm 29. The outer end of arm 29 is preferably fitted with a roller 33 on which the arm 28 rides when in contact therewith. The gear 13 is also provided with an arm 34 arranged to contact at predetermined intervals in the rotation of the gear with a lateral extension 35 secured to the discharge door 6 and depress the same, thus opening the door, which is returned to its normal closed position when the arm 34 passes the extension by the spring hinge 8. The extension 35 is also provided with a roller 36 on which the arm 34 rides when in contact therewith.

It will, of course, be obvious that the opening of the doors 5 and 6 may be regulated by increasing or decreasing the ratio of the respective gears one to the other.

The foregoing description of the door opening and closing means is, however, merely illustrative; there are other well-known and obvious means of effecting the opening and closing movements any of which may be employed.

The manner in which the machine operates and its utility will be readily understood, as it will be seen that on rotating 10 the shaft 9 by means, say, of a belt drive connected to pulley 10 the mixing plates 20, 21, 22, 23, 24 and 25 and the gears 11, 12 and 13 will be caused to rotate and feed ingredients will be admitted into the chamber 1 15 from the hopper 26 and discharges therefrom at predetermined intervals as the 5 and 6 respectively open and close. Due to the alternate and inclined arrangement of the mixing blades, as hereinafter described, 20 25 the ingredients discharged from the hopper are not only carried around by the plates but are in addition thrown in towards the centre of the machine so that a thorough mixing is effected due to the combined rotary and lateral movements to which the ingredients are subjected so that the feed is discharged from the chamber in a perfectly mixed state.

From the foregoing it will be seen that I 30 have devised a simple, practical, and efficient machine the use of which enables poultry, cattle, or other feeds to be thoroughly mixed with the utmost facility and convenience.

What I claim as my invention is:

35 1. A feed mixing machine comprising, a mixing chamber having an upper inlet opening and a lower discharge opening, doors for each opening normally closing them, a plurality of equidistantly spaced 40 circumferentially arranged longitudinal blades rotatable within said chamber each broader at one end than the other, alternate blades being reversely disposed to the other blades with reference to their broad and narrow ends, and means automatically operative 45 to open the respective doors at predetermined intervals in the rotation of the said blades.

50 2. A feed mixing machine comprising, a mixing chamber having an upper inlet opening and a lower discharge opening, doors for each opening normally closing them each having an extension projecting beyond the end of the chamber, a rotatable shaft extending longitudinally through the chamber and exteriorly thereof at its opposite ends and provided on one exterior end with a gear, a plurality of equidistantly spaced circumferentially arranged longitudinal blades within the chamber carried by said shaft, and rotatably mounted gears meshing with said shaft gear each having

an arm arranged to contact respectively with the respective door extensions at a predetermined point in their rotary movement and carry the extensions forwardly an amount sufficient to open their respective doors.

3. A feed mixing machine comprising, a mixing chamber having an upper inlet opening and a lower discharge opening, spring-pressed doors for each opening normally closing them each having an extension projecting beyond the end of the chamber, a rotatable shaft extending longitudinally through said chamber and exteriorly thereof at its opposite ends and provided on one exterior end with a gear, a plurality of equidistantly spaced circumferentially arranged longitudinal blades within the chamber carried by said shaft, each blade being broader at one end than the other and alternate blades being reversely disposed to the other blades with reference to their broad and narrow ends, and rotatably mounted gears meshing with the said shaft gear each having an arm arranged to contact respectively with the respective door extensions at a predetermined point in their rotary movement and carry the extensions forwardly an amount sufficient to open their respective doors and then pass clear of the extensions.

4. A feed mixing machine comprising, a mixing chamber having an upper inlet opening and a lower discharge opening, spring-pressed doors for each opening normally closing them each having an extension projecting beyond the end of the chamber, a rotatable shaft extending longitudinally through said chamber and exteriorly thereof at its opposite ends and provided on one exterior end with a gear, a plurality of equidistantly spaced circumferentially arranged longitudinal blades within the chamber carried by said shaft each blade being broader at one end than the other and alternate blades being reversely disposed to the other blades with reference to their broad and narrow ends, all of said blades being concaved facing their direction of rotation and having their narrow ends closer to the shaft than the broad ends, and rotatably mounted gears meshing with said shaft gear each having an arm arranged to contact respectively with the respective door extensions at a predetermined point in their rotary movement and carry the extensions forwardly an amount sufficient to open their respective doors and then pass clear of the extensions.

Dated at Ocean Falls, B. C. this 9th day of August, 1924.

FRANK ASPDEN.
